UNITED STATES PATENT OFFICE

152,663

DESIGN FOR A VEHICLE SIGNAL CASING

Mike Steigel, Rapides Parish, near Alexandria, La.

Application January 9, 1948, Serial No. 143,604

Term of patent 7 years

(Cl. D72—1)

To all whom it may concern:

Be it known that I, Mike Steigel, a citizen of the United States of America, residing at Rapides Parish, near Alexandria, State of Louisiana, have invented a new, original, and ornamental Design for Vehicle Signal Casings, of which the following is a specification, reference being had to the accompanying drawing, forming part thereof.

Fig. 1 is a side elevational view of a vehicle signal casing, showing my new design.

Figs. 2 and 3 are front and rear elevational views, respectively, of the same.

Fig. 4 is a top plan view of the same.

I claim:

The ornamental design for a vehicle signal casing, as shown.

MIKE STEIGEL.
